UNITED STATES PATENT OFFICE.

CHARLES A. BRYANT, OF WAKEFIELD, MASSACHUSETTS, ASSIGNOR TO CONSOLIDATED SAFETY PIN COMPANY, OF BLOOMFIELD, NEW JERSEY, A CORPORATION OF NEW JERSEY.

CLASP.

SPECIFICATION forming part of Letters Patent No. 706,522, dated August 12, 1902.

Application filed March 17, 1902. Serial No. 98,535. (No model.)

To all whom it may concern:

Be it known that I, CHARLES A. BRYANT, a citizen of the United States, whose residence and post-office address is Wakefield, in the county of Middlesex, State of Massachusetts, have invented certain new and useful Improvements in Clasps, of which the following is a specification, reference being had to the accompanying drawings.

10 This invention relates to clasps such as are commonly employed on garments either with or without additional fastening devices, such as buttons and the like; and the object of the invention is to simplify and improve the 15 construction of such clasps, as well as to increase their facility in use and their effectiveness in operation.

The invention will be more fully described hereinafter with reference to the accompanying 20 drawings, in which it is illustrated, and in which—

Figures 1 and 2 are respectively a side view and a front view of a clasp without the spring and parallel grip hereinafter referred 25 to, the clamping-lever being shown in Fig. 1 by full lines in its partly-open position and by dotted lines in its closed position. Figs. 3 and 4 are similar views, but showing the spring coöperating with the clamping-lever 30 and teeth on the frame. Figs. 5 and 6 are longitudinal sectional views of the clasp shown in Figs. 3 and 4, the clamping-lever being shown in its closed and open positions in the two figures, respectively. Fig. 7 is a 35 side view of a clasp similar to that shown in Fig. 3, but with the parallel grip applied to the clamping-lever. Fig. 8 is a perspective view, on a somewhat-larger scale, of the clasp shown in Fig. 7. Fig. 9 is a side view of a 40 clasp similar to that shown in Fig. 7, but with the parallel series of teeth and without the spring. Figs. 10 and 11 are respectively a longitudinal central section and a transverse section of the clasp shown in Fig. 9.

45 In the form represented in Figs. 1 and 2 the clasp comprises a U-shaped frame *a*, which is stiff enough to hold the material firmly and yet sufficiently resilient to coöperate properly with the clamping-lever. One 50 member of the frame, as *b*, may be plain.

The other member, as *c*, is slotted, as indicated by dotted lines in Fig. 1, and is provided or formed with ears *d*. The clamping-lever comprises a handle *e* and a clamping-jaw *f*, disposed substantially at right angles 55 to the handle, integral pivots being formed, as at *g*, to engage the ears *d*. The clasp thus formed is practically operative, the opposing member *b* of the frame yielding sufficiently to coöperate with the clamping-jaw both to 60 accommodate the fabric and to hold the jaw when it is in its closed position.

For convenience in use it is desirable that the simple clasp shown in Figs. 1 and 2 be provided with a spring *h* to coöperate with 65 the clamping-lever, as shown in Figs. 5 and 6, for the purpose of holding it either in its closed position or in its open position. The spring may be secured to the frame in any convenient manner. Its free end is arranged 70 to bear against the clamping-jaw above the pivot, as shown in Fig. 6, when the clamping-lever is in its open position and below the pivot, as shown in Fig. 5, when the clamping-lever is in its closed position, thereby 75 holding the lever in either of such positions. To prevent the free end of the spring from rising too far when the lever is in its open position, as shown in Fig. 6, a stop *e'* is formed on or applied to the under side of the 80 handle *e* in position to engage the free end of the spring, and when the clamping-lever is moved to its closed position to bear against the spring and thrust it downward, so that the end thereof shall press against the clamping-jaw below the pivot. Teeth *i* may also 85 be advantageously applied to or formed on the member *b* of the frame to coöperate with the clamping-jaw, as shown in Figs. 4 and 5. For the purpose of affording a broader surface of contact with the fabric than is afforded by the edge of the clamping-jaw a parallel grip or presser-foot *k* may be pivoted to the lower edge of the clamping-jaw on an axis 90 parallel with the axis of the clamping-jaw, as 95 shown in Figs. 7 and 8, such presser-foot adapting itself to the fabric as it lies on the opposing member *b* of the frame. As indicated in Fig. 8, the lower edge of the clamping-jaw *f* may be formed with integral piv- 100

ots *f'*, which engage sockets formed therefor by the overturned edges *k'* of the parallel grip or presser-foot *k*. When a very firm and positive grasp of the fabric is desired, it is preferable to provide the opposing member *b* of the frame with parallel series of teeth *l*, between which the presser-foot or parallel grip *k* may enter, forcing the fabric down into engagement with the preferably-pointed teeth *l* and retaining it in such engagement, so that there is no possibility of slipping. The clamping-jaw *f* may be provided, as shown in Figs. 8 and 11, with integral pivots *f'* to engage the overturned edges *k'* of the presser-foot or parallel grip, and the teeth *l* may be conveniently formed by turning inward upon themselves the edges *b'* of the blank from which the frame is formed, the edges being then turned upward to form the upwardly-projecting teeth *l*. The edges of the member *c* of the frame may also be turned inward, as at *c'*, to support the pivots *g* of the clamping-lever.

As will now be obvious, the improved clasp is not only exceedingly simple in construction, and therefore comparatively inexpensive to manufacture, but it is direct and positive in its action and grasps and holds the fabric firmly.

30 I claim as my invention—

1. A clasp comprising a U-shaped frame, a clamping-lever pivoted on one member of the frame and having a clamping-jaw to coöperate with the other member and directly engage the fabric and a handle, and a spring secured to said frame and coöperating with said clamping-lever to hold it in either its open or closed position, substantially as described.

40 2. A clasp comprising a U-shaped frame having one member provided with teeth, a clamping-lever pivoted on one member of the frame and having a clamping-jaw to coöperate with the toothed member and directly engage the fabric, and a handle, and a spring secured to said frame and coöperating with said clamping-lever to hold it in either its

open or closed position, substantially as described.

3. A clasp comprising a U-shaped frame, a clamping-lever pivoted on one member of the frame and having a clamping-jaw to coöperate with the other member, and a handle, and a presser-foot pivoted on said clamping-jaw on an axis parallel with the axis of the clamp-jaw, substantially as described.

4. A clasp comprising a U-shaped frame, a clamping-lever pivoted on one member of the frame and having a clamping-jaw to coöperate with the other member, and a handle, a presser-foot pivoted on said clamping-jaw on an axis parallel with the axis of the clamp-jaw, and a spring secured to said frame and coöperating with said clamping-lever to hold it in either its open or its closed position, substantially as described.

5. A clasp comprising a U-shaped frame having on one member two longitudinal, parallel series of teeth, a clamping-lever pivoted on the other member of the frame and having a clamping-jaw and a handle, and a presser-foot pivoted on said clamping-jaw on an axis parallel with the axis of the clamping-jaw and adapted to enter between said series of teeth.

6. A clasp comprising a U-shaped frame having on one member two longitudinal, parallel series of teeth, a clamping-lever pivoted on the other member of the frame and having a clamping-jaw and a handle, a presser-foot pivoted on said clamping-jaw on an axis parallel with the axis of the clamping-jaw and adapted to enter between said series of teeth, and a spring secured to said frame and coöperating with said clamping-lever to hold it either in its open or its closed position, substantially as described.

This specification signed and witnessed this 13th day of March, A. D. 1902.

CHARLES A. BRYANT.

In presence of—

CHARLES F. HARTSHORNE,
FREDERIC S. HARTSHORNE.
